ASH TRAY

George T. James, Pasadena, Calif., assignor to Gladding,
McBean & Co., Los Angeles, Calif., a corporation of
California

Application December 10, 1954, Serial No. 33,479

Term of patent 14 years

(Cl. D85—2)

Fig. 1.

Fig. 2.

Fig. 3.

Fig. 1 is a top plan view of an ash tray showing my new design.

Fig. 2 is a bottom view thereof; and

Fig. 3 is an enlarged section of a portion of the ash tray, the section being taken along plane III—III in Fig. 1.

I claim:

The ornamental design for an ash tray, as shown.
